FOAM APPLICATOR

Thomas H. Warnock, Bayonne, N. J., assignor to
Standard Oil Development Company, a corpora-
tion of Delaware

Application October 18, 1932, Serial No. 638,302

7 Claims. (Cl. 169—4)

This invention relates to improvements in fire fighting equipment for storage tanks, and more particularly relates to an improved portable foam applicator.

5 The invention will be fully understood from the following description taken in connection with the accompanying drawings in which latter—

Fig. 1 is a side elevational view of the device assembled at the side of a storage tank.

10 Fig. 2 is a top plan view of the mixing chamber.

Fig. 3 is a detailed side elevational view of the mixing chamber with parts broken away.

Fig. 4 is a bottom plan view of the mixing chamber, and

15 Fig. 5 is a perspective view of the apparatus in use.

Referring particularly to the drawings, the foam applicator is described as applied to an oil tank 1, the mixing chamber being partially elevated up 20 the side of the tank in Fig. 1. The oil contents of the tank sometimes catch on fire and the portable foam applicator functions as an efficient means for rapidly applying fire extinguishing foam to the upper surface of the burning body of oil. Refer-

25 ence numeral 2 designates a portable pole made for example of $1\frac{1}{2}$ " pipe bent into a hooked form 3 at one end. The handle end of the pole is provided with hand grips 4. A handle 5 extends at right angles to the handle end of the pole. The 30 handle 5 is provided with a socket member 6 which is welded to the handle and is adapted to receive the handle end of the pole 2. The socket member 6 and the base of the pole are provided with aligned slots adapted to receive a suitable bolt 7

35 to lock the connection there-between.

Light hand poles 10 and 11 with their extensions 10' and 11' are connected to the portable pole 2 part way up the portable pole. The connection is formed by means of a sliding collar 12 which in 40 service is rigidly secured to the pole 2 at some height depending upon the height of the tank. The collar 12 carries projecting ears 13 which are connected by suitable rings 14 to the hand poles 10 and 11. The hand poles 10 and 11 function to 45 assist in raising the pipe pole 2 to a vertical position elevated sufficiently to enable the hooked end 3 to hook over the top angle of the tank 1.

A mixing chamber 20 is then hoisted into position to deliver foam or the like from its discharge 50 end 21 over the edge of the tank 1. The mixing chamber is hoisted by means of the pulley blocks 22 and 23 and the tackle 24 constituting a block and fall. The tackle 24 is preferably made of steel cable and the pulley blocks 22 and 23 are 55 preferably made of steel. The pulley block 22 is

secured to the mixing chamber 20 by means of a flat iron 26 having an eye 27 suitably secured to the mixing chamber. The pulley block 23 is secured to the main pulley 2 by means of a ring 30. The mixing chamber is provided with inlet 60 lines 31 and 32. Prior to raising the mixing chamber, hose lines 31'—32' see Fig. 5, are connected to the inlet lines 31 and 32. The hose lines lead from a suitable source of foam making material, not shown. The material is mixed together in the 65 mixing chamber and delivered as foam through the downwardly facing delivery end 21.

By the apparatus described, the foam applicator can be speedily and manually positioned to deliver fire extinguishing foam directly upon the 70 surface of the burning oil in a tank. The apparatus can be transported manually, hastily through narrow places over lines, concrete walls and the like to the tank containing the burning contents.

Various changes may be made within the scope 75 of the appended claims in which it is desired to claim all novelty inherent in the invention as broadly as the prior art permits.

I claim:

1. A foam applicator for a tank the contents 80 of which are burning, comprising a portable pole of a length substantially equal to the height of the tank and having a hooked end adapted to be hooked over the top edge of the tank, a mixing chamber of lesser length than the pole and 85 having a delivery end, and means connected to the hooked end of the portable pole and to the chamber whereby the delivery end of the chamber can be hoisted from the ground to a position 90 over the top edge of the tank.

2. A foam applicator for a tank the contents 95 of which are burning, comprising a mixing chamber, a portable pole of a length substantially equal to the height of the tank having a hooked end adapted to be hooked over the top edge of the tank, and a hoist connected to the hooked end of the pole and to the chamber whereby the delivery end of the chamber can be hoisted from the ground to a position over the top edge of the tank.

3. A foam applicator for a tank the contents 105 of which are burning, comprising a mixing chamber, a portable pole of greater length than the mixing chamber and of a length substantially equal to the height of the tank and having a 105 hooked end adapted to be hooked over the top edge of the tank, hand poles of lesser length than the portable pole connected to an intermediate portion of the portable pole, and a hoist connected to the hooked end of the portable pole and 110

to the chamber whereby the delivery end of the chamber can be hoisted from the ground to a position over the top edge of the tank.

4. In a hoisting device for the mixing chamber of a foam applicator for a tank the contents of which are burning, a portable pole of a length substantially equal to the height of the tank and having a hooked end adapted to be hooked over the top edge of the tank, and means connected to the hooked end of the pole and adapted to be connected to the mixing chamber whereby the delivery end of the chamber can be hoisted from the ground to a position over the top edge of the tank.
5. In a hoisting device for the mixing chamber of a foam applicator for a tank the contents of which are burning, a portable pole of a length substantially equal to the height of the tank and having a hooked end adapted to be hooked over the top edge of the tank, hand poles connected to an intermediate portion of the portable pole, and means connected to the hooked end of the pole and adapted to be connected to the chamber whereby the delivery end of the chamber can be hoisted over the top edge of the tank.

6. In a hoisting device for the mixing chamber of a foam applicator for a tank the contents of which are burning, a portable pole of a length substantially equal to the height of the tank and having a hooked end adapted to be hooked over the top edge of the tank, jointed hand poles connected to an intermediate portion of the portable pole, and means connected to the hooked end of the pole and adapted to be connected to the chamber whereby the delivery end of the chamber can be hoisted over the top edge of the tank.

7. In a hoisting device for the mixing chamber of a foam applicator for a tank the contents of which are burning, a portable pole of a length substantially equal to the height of the tank and having a hooked end adapted to be hooked over the top edge of the tank, hand poles connected to an intermediate portion of the portable pole, and a steel block and fall connected to the hooked end of the pole and adapted to be connected to the chamber, whereby the delivery end of the chamber can be hoisted over the top edge of the tank.
